BOTTLE FILLER

Ralph T. Salsbury, Oakland, Calif.

Application May 11, 1931. Serial No. 536,470

6 Claims. (Cl. 226—77)

This invention relates to improvements in bottle fillers and particularly to combined bottle fillers and cappers.

In this connection attention is directed to my 5 copending application for patent, filed April 29, 1930, entitled Bottle fillers and cappers and bearing Serial Number 448,224.

The principal object of the invention is to simplify the mode of operation and the means for 10 filling and capping bottles.

Another object is to prevent leakage at the filler between the bottle filling operations.

A further object is to provide an improved holding, clinching and crimping means for 15 "crown" caps.

Other objects and advantages will appear as the description progresses.

In this specification and the accompanying drawings the invention is disclosed in its preferred form. It is to be understood, however, 20 that it is not limited to this form because it may be embodied in other forms within the spirit of the claims following the description.

In the two sheets of drawings:

25 Fig. 1 is a vertical section of a combined filler and capper constructed in accordance with this invention.

Fig. 2 is a similar view of the same in the bottle filling position.

30 Fig. 3 is a similar view of the same in the bottle capping position.

Fig. 4 is a similar view of a modified form of portable bottle filler in the closed position.

35 Fig. 5 is a similar view of the same in the bottle filling position.

Fig. 6 is a side elevation of the modified form complete with the handle and vent.

In detail the construction illustrated in the drawings, referring to Fig. 1, comprises the outer shell 1, having the chamfered opening 2 at the bottom. Its upper portion or head 3 has the threaded central opening therethru to receive the threaded end 4 of the plunger of the capping machine. The interior opening of the shell has the 40 annular shoulder 5 and is recessed at 6 and vented through the head at 7 to receive the nipple 8. The side of the shell is slotted at 9 to clear the filler nipple 10. This shell 1 rises and falls with the plunger stud 4 to cap the bottle X resting upon the base of the capping machine in the usual manner.

50 The filler valve mechanism consists of an inverted elastic cup 11, of tough vulcanized rubber stock. The annular plug 12 of softer elastic stock is inserted in the bottom of the cup 11 which

it fits snugly and with which it forms a hermetic bond. The parts 11—12 coact as a unit to form the chamber 13. The valve seat 14 is formed in the bottom of the plug 12. The valve 15 cooperates with the seat 14 and has the tubular stem 16, extending thru the top 17 of the cup 11, which it engages between the flange 18—19. The elasticity of the walls and the top 16 of the cup 11 normally pull the valve 15 snugly against the soft seat 14. The valve and stem 15—16 65 may be formed of non-corrosive metal, bakelite or any suitable material.

The hollow collapsible cushion 20 is set within the recess 6 and is provided with alined perforations 21—22 communicating with the vent 7 and 70 the tubular stem 16.

The annular ring 23 surrounds the plug 12 to which it adheres and stops against the shoulder 5.

The bottle X is placed in the capping machine 75 under the plunger 4 as in Fig. 2. When the plunger descends, the ring 23 engages the top of the bottle which pushes the ring up to the stop shoulder 5. This raises the cup 11 until the end 19 of the stem 16 impinges on the cushion 20. The resistance of the cushion depresses and collapses the top 17 of the cup 11. The completion of the upward movement of the ring 23 thus raises the seat 14 off the valve 15. As the plunger 4 rises the valve 14—15 closes as in Fig. 1.

80 The crown cap Y is placed on top of the bottle under the bottom 2 of the shell and the plunger 4 again forced down to clinch the cap onto the neck of the bottle, in the usual manner. The presence of the cap carries the valve 15—16 upward, which compresses the cushion 20. The resistance of the cushion is sufficient to depress or crimp the center of the cap Y, which further compresses the cork gasket Z between the cap and 85 the mouth of the bottle insuring perfect sealing of the bottle closure.

90 This invention operates substantially as follows: The liquid flows thru the nipple 10 into the chamber 13 and is stopped by the valve 14—15 as in Fig. 1. If the liquid is siphoned, the flow can be started by applying suction to the vent nipple 8 after the bottle X is inserted in the machine.

95 Insertion of the bottle as in Fig. 2 opens the valve 14—15, permitting the liquid to flow into the bottle. The liquid is directed against the sides of the bottle down which it flows, while the air impounded in the bottle flows upward thru the tubular valve stem 16 and escapes at the vent 7. If foaming liquids are being handled they will 100 flow into the bottle without effervesing, if di-

rected against the sides of the bottle as stated, and the impounded air is given a free outlet. If there is any mingling of such liquid with the outgoing air, regurgitation is set up and filling of the bottle is prevented.

When the pressure against the mouth of the bottle is removed the resilient walls and top 17 of the cup 11 expand and draw the valve 15 against its seat 14. This seat being of soft rubber it insures a perfect stopping of the liquid, even in the presence of ordinary obstructive solid particles suspended in the liquid, which cause an after drip at the filler when other forms of valves are used. The extended annulus of the valve at 15 24 of soft rubber seals the mouth of the bottle against overflow during the filling operation, see Fig. 2.

In addition to the mechanical effectiveness and simplicity of the resilient chamber 13 it protects 20 the liquid from contact with the metal parts of the apparatus. All the parts contacting the liquid can be of soft and hard rubber respectively and easily maintained in a sanitary condition.

The modified form of this invention shown in 25 Figs. 4-5-6 is similar in construction and mode of operation to that previously described, except that the capping mechanisms are omitted. For identification the various parts will be given the same reference characters previously used, with 30 the addition of the character *x*. This modification is especially useful for rapidly filling bottles arranged en masse. The handle 4*x* is substituted for the plunger 4 through which the tubular vent 7*x* extends and is bent laterally so that the hand 35 of the operator will not close it. When the ring 23*x* is pressed down upon the neck of the bottle the walls of the chamber 13 compress and open the valve 14*x*-15*x*. Lifting the handle 4*x* automatically closes the valve. The shell 1*x* merely 40 acts to guide the top of the bottle under the valve and to give stability to the device in operation.

Having thus described this invention what is

claimed and desired to secure by Letters Patent is:

1. A filler including a shell having an internal shoulder, resilient walls within said shell forming a chamber and having a valve seat therein, a ring 80 encircling said seat and adapted to engage said shoulder, a valve engaging said seat and having a hollow stem engaging said walls.

2. A filler including a shell having a vent therefrom; a resilient wall within said shell forming a chamber with a valve seat therein; a valve engaging said seat and having a hollow stem engaging said wall and said shell and communicating with said vent.

3. A filler including a shell; a resilient wall 90 within said shell forming a chamber with openings in its opposite sides respectively; a valve engaging one of said openings and having a stem fixed in the opposite opening and a cushion interposed between said shell and the end of said stem.

4. A filler including a shell with a top vent and a side opening and having an internal shoulder; a wall within said shell forming a chamber having openings in its opposite sides; a valve engaging one of said openings and having a hollow stem 100 communicating with said vent and engaging the other opening, a cushion interposed between said stem and the top of said shell and a nipple extending through a side opening and communicating with said chamber.

5. A filler including a shell; a compressible wall, and a collapsible top within said shell forming a chamber with a valve seat therein; a valve engaging said seat and having a stem engaging said top and said shell.

6. A filler including a shell having a vent therefrom; a compressible wall and a collapsible top within said shell forming a chamber with a valve seat therein; a valve engaging said seat and having a hollow stem engaging said top and said shell 115 and communicating with said vent.
